Primary Examiner — Marianne Pandozzi(74) *Attorney, Agent, or Firm* — Barnes & Thornburg LLP(57) **CLAIM**

What is claimed is the ornamental design for a brewer, as shown and described.

DESCRIPTION

FIG. 1 is a front perspective view thereof;
 FIG. 2 is a front elevational view thereof;
 FIG. 3 is a right side elevational view thereof and the left side elevational view being a mirror image thereof;
 FIG. 4 is a rear elevational view thereof;
 FIG. 5 is a top view thereof; and,
 FIG. 6 is a bottom view thereof.
 The broken lines shown in the drawings are for purposes of illustrating portions of the brewer and form no part of the claimed design.
